(57) **CLAIM**

I claim the ornamental design for a video CD case, as shown and described.

DESCRIPTION

FIG. 1 is an isometric view of a video CD case showing my new design; and

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof; and,

FIG. 7 is a bottom plan view thereof.

The broken lines showing in FIGS. 1, 2, 4, 5, 6, and 7 are for the purpose of illustrating the environment of the design only and form no part of the claimed design.
